Attorneys.

UNITED STATES PATENT OFFICE.

JOHN PAUL RAGSDALE, OF COLLEGE PARK, GEORGIA.

LOCK.

Application filed May 24, 1924. Serial No. 715,648.

To all whom it may concern:

Be it known that I, JOHN P. RAGSDALE, a citizen of the United States, residing at College Park, in the county of Fulton and State of Georgia, have invented a new and useful Lock, of which the following is a specification.

This invention relates to a novel form of screen securing device, the primary object 10 of the invention being to provide a device of this character especially designed for removably securing window screens in passenger coaches, so that the screens may be readily and easily removed to facilitate the 15 cleaning of the windows.

Another important object of the invention is to provide a device of this character which may be readily and easily manipulated, eliminating the necessity of using 20 tools to accomplish the removal of the screens.

A still further object of the invention is to provide means for holding the screens securely against movement while in the 25 window frames, thereby insuring against rattling of the screens while in use.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 35 within the scope of what is claimed, without departing from the spirit of the invention.

Referring to the drawing:

Figure 1 is a fragmental elevational view disclosing a securing device constructed in accordance with the invention as in its active or securing position, dotted lines indicating the position of the securing device when in its inactive position.

Figure 2 is a sectional view taken on line 45 2-2 of Figure 1.

Figure 3 is a sectional view taken on line 3-3 of Figure 1.

Referring to the drawing in detail, the reference character 5 indicates one of the bars of a window frame which is formed with grooves 6 to accommodate the screen sections 7 that screen the windows of the coach.

The device forming the essence of the invention includes a supporting plate 8

formed with an opening 9 to accommodate the bolt 10 which is provided with a head 11 on its inner end. The outer end of the bolt is formed with threads to permit the knob 11 to be secured thereto, which knob 60 affords means whereby the device may be operated.

A coiled spring indicated at 12 surrounds a portion of the bolt and contacts with the head 11 at one of its ends, the opposite end 65 of the spring contacting with the plate 8 so that as the bolt 10 is moved outwardly, the spring is compressed.

It might be further stated that the bar 5 is cut away as at 13 to accommodate the bolt. Supported by the bolt and adapted to move therewith is a securing arm 14 which is formed with inwardly extended end portions 15 adapted to contact with the screen frames to hold them in position. 70 In order that the arm 14 will be held in its active position against accidental movement, flanges 16 are provided on the plate 8, the flanges being of sufficient size to allow the arm 14 to lie therebetween when 75 the arm is in its active or securing position.

When the arm is in its active position, and it is desired to remove the screens secured thereby, it is only necessary to pull the knob 11 compressing the spring and 80 moving the arm 14 from its positions between the flanges 16, whereupon a slight rotation of the knob 11 results in the arm 14 being moved to a position as shown in dotted lines in Figure 1, or out of engagement with the screens. It is obvious that 85 the screens may now be readily and easily removed from their positions in the window frames.

I claim:

A screen securing device including a spring pressed arm, said arm adapted to contact with adjacent screens to hold them in position, said arm adapted to be rotated to a vertical position and out of engagement 90 with the screen, and means for engaging the arm and restricting movement of the arm.

In testimony that I claim the foregoing as my own, I have hereto affixed my signature in the presence of two witnesses.

JOHN PAUL RAGSDALE.

Witnesses:

J. F. BANKNIGHT,
A. S. ALLEN.
